Inventor:
Victor E. Goodwin,
by Alexander S. Lunt,
His Attorney.

UNITED STATES PATENT OFFICE.

VICTOR E. GOODWIN, OF PITTSFIELD, MASSACHUSETTS, ASSIGNOR TO GENERAL ELECTRIC COMPANY, A CORPORATION OF NEW YORK.

CONDENSER SWITCHING APPARATUS.

Application filed May 12, 1924. Serial No. 712,568.

My invention relates to an alternating current system in which static condensers are employed for the purpose of improving the power factor of the circuit. In a system of this nature, throwing the condenser directly on and off the line gives rise to objectionable surges. These may be reduced by the use of series resistances but for economic reasons it is not desirable to employ resistances permanently connected in circuit with the condensers. It is nevertheless very desirable to allow the condensers to discharge through a resistance as soon as they are taken off the line. An object of my invention therefore is to provide in a system of the type noted above an improved means whereby the condensers may be thrown on and off the line without causing objectionable surges thereon and whereby the condensers after being disconnected from the line may quickly be discharged.

My invention will be better understood from the following description taken in connection with the accompanying drawing, and its scope will be pointed out in the appended claims.

In the drawing, Fig. 1 is a diagrammatic representation of my invention; Fig. 2 is a similar representation of a modified form, and Fig. 3 shows a switch partly in cross section which may comprise a part of the apparatus shown in Fig. 2.

Referring first to Fig. 1, a three phase line 1 is shown adapted to be connected by means of switches 2 to the static condensers 3 through the resistances 4. Reactances 5 are also shown in the connections to the condensers which reactances may, for example, produce a reactance drop of about 20 per cent. As shown in Fig. 1 each of the three switches 2 comprises three pairs of stationary contacts and two cooperating movable contacts. The two upper contacts 7 are shown somewhat longer than the middle contacts 8 or the lower contacts 9 and the distance between the movable contact arm 10 and the contacts 7 is less than the distance between the contact arm 11 and the contacts 8. The movable contact arms 10 and 11 of each switch are connected to be shifted by an operating rod 12 and the three rods 12 are connected to cranks 13 on an operating shaft 14. When the operating rod of each switch is raised from the position illustrated in Fig. 1 the lower contact arm

11 is first disengaged from the lower contacts 9. Continued upward movement of the operating rod first brings the upper contact arm 10 in engagement with the upper contacts 7 and then as the arm 10 slides over contacts 7 the lower arm 11 engages contacts 8. With the switches connected between the line and the condensers, resistances and reactances as illustrated in Fig. 1 and with the contact arms in their lowermost position, the condensers 3 are short circuited through the resistances 4. Upon raising the operating rods 12 the short circuit connection is first opened and then the condensers are connected to the line through the resistances. Further upward movement of the operating levers short circuits the resistances, thus in effect connecting the condensers directly to the line. Conversely the reverse movement of the operating levers first opens the short circuit across the resistances, next breaks the connection with the line and finally connects the condensers directly to the resistances and reactances through which they may discharge.

In the form of the invention illustrated by Figs. 2 and 3 each switch has but two pairs of stationary contacts 7 and 8 which correspond in their spacing and in their connections to the upper and middle pairs of contacts 7 and 8 of Fig. 1, the lower pair of contacts 9 of Fig. 1 being incorporated in a separate switch 16. This switch 16 is shown comprising three bridging contacts arms 17 which are simultaneously actuated by an operating rod 18 connected by crank 19 to the shaft 14. In this modification separate resistances 20 are employed and connected to be controlled by the switch 16 through which resistances the condensers are discharged when thrown off the line. The operating connection of the switch 16 with shaft 14 is such that the circuits of the resistances 20 are opened before the condensers are thrown upon the line and are closed after the condensers are taken off the line as in Fig. 1. With the exception that separate resistances are employed for initially connecting the condensers to the line and for discharging them, the operation of the modification illustrated by Fig. 2 is similar to that illustrated by Fig. 1.

Where the arrangement is like that shown by Fig. 2, switches of the type illustrated by Fig. 3 may be used for controlling the

connections between the condensers and the line. This is a standard three phase double break oil switch in which the middle set of contacts have been replaced by the resistances 4 and the stationary contacts 7 of one set are longer than the stationary contacts 8 of the other set so that when the switch is opened the break occurs at the contacts 8 before it occurs at the contacts 7. The switch is shown comprising the usual oil tank 22 supported from the frame 23 with the stationary contacts carried by insulating bushings 24, the middle bushing used to support the resistances 4.

15 While I have described certain embodiments only of my invention, I do not wish to be limited to the particular forms shown and described as it will be apparent that many modifications therein may be made 20 without departing from the scope of my invention as set forth in the appended claims.

What I claim as new and desire to secure by Letters Patent of the United States, is:—

25 1. The process of connecting and disconnecting a condenser with and from a line which consists in connecting the condenser with the line with interposed resistance and inductance and thereafter short circuiting the resistance disconnecting the condenser 30 from the line, removing the short circuit from the resistance and then disconnecting the resistance and the condenser from the line and thereafter shunting the condenser with said resistance.

35 2. In combination with a three phase line, a delta connection with a condenser in each side of the delta, each apex of the delta having a separate branch conductor connected thereto, an inductance element and a resistance element in each branch, means for connecting the end of one of said branches with one side of said line and the end of a second one of said branches with a second side of said line and the end of the third one of 40 said branches with the third side of said line, and for disconnecting said branches from said line, and for shunting all of the sides of the delta simultaneously after the branches have been disconnected from the line, means for preventing the sides of the delta from being shunted while the branches are connected to the line, and means for preventing the resistance elements from being shunted while the branches are disconnected from the line.

45 3. In combination with a three phase line, a delta connection with a condenser in each side of the delta, each apex of the delta having a separate branch conductor connected thereto, an inductance element and a resistance element in each branch, means for connecting the end of one of said branches with one side of said line and the end of a second 50 side of said line and the end of the third one of said branches with the third side of said line, and for disconnecting said branches from said line, and for shunting all of the sides of the delta simultaneously after the branches have been disconnected from the line, and means for preventing the resistance elements from being shunted while the branches are disconnected from the line.

55 one of said branches with a second side of said line and the end of the third one of said branches with the third side of said line, and for disconnecting said branches from said line, and for shunting all of the sides of the delta simultaneously after the branches have been disconnected from the line, means for preventing the sides of the delta from being shunted while the branches are connected with said line, means for shunting said resistance elements simultaneously after the branches have been connected to the line.

60 4. In combination with a three phase line, a delta connection with a condenser in each side of the delta, each apex of the delta having a separate branch conductor connected thereto, an inductance element and a resistance element in each branch, means for connecting the end of one of said branches with one side of said line and the end of a second one of said branches with a second side of said line and the end of the third one of said branches with the third side of said line, and for disconnecting said branches from said line, and for shunting all of the sides of the delta simultaneously after the branches have been disconnected from the line, means for preventing the sides of the delta from being shunted while the branches are connected with said line, and means for shunting said resistance element simultaneously after the branches have been connected to the line.

65 5. In combination with a three phase line, a delta connection with a condenser in each side of the delta, each apex of the delta having a separate branch conductor connected thereto, an inductance element and a resistance element in each branch, means for shunting the sides of the delta simultaneously and for removing said shunt, means for connecting the end of one of said branches with one side of said line and the end of a second one of said branches with a second side of said line and the end of the third one of said branches with the third side of said line, and means for preventing the sides of the delta from being shunted while the branches are connected with the line.

70 6. In combination with a three phase line, a delta connection with a condenser in each side of the delta, each apex of the delta having a separate branch conductor connected thereto, an inductance element and a resistance element in each branch, means for connecting the end of one of said branches with one side of said line and the end of a second one of said branches with a second side of said line and the end of the third one of said branches with the third side of said line, and for disconnecting said branches from said line, and for shunting all of the sides of the delta simultaneously after the branches have been disconnected from the line, and means for preventing the resistance elements from being shunted while the branches are disconnected from the line.

sides of the delta from being shunted while of the three phase line and for connecting the branches are connected with said line. the other end of a second branch with a 40

7. In combination with a three phase line, a delta connection with a condenser in each side of the delta, each apex of the delta having a separate branch conductor connected thereto, an inductance element and a resistance element in each branch, means for connecting the end of one of said branches with one side of said line and the end of a second one of said branches with a second side of said line and the end of the third one of said branches with the third side of said line, and for disconnecting said branches from said line, and for shunting all of the sides of the delta simultaneously after the branches have been disconnected from the line. 45

8. In combination with a three phase line, a delta connection with a condenser in each side of the delta, each apex of the delta having a separate branch conductor connected thereto, an inductance element and a resistance element in each branch, means for shunting all of the sides of the delta simultaneously and all the resistance elements simultaneously, and for connecting said branches each to a separate side of the said line. 50

9. In combination with a three phase line, three condensers, one interposed in each side of a delta connection, three branch lines, one for each apex of the delta, one end of each branch being connected to the corresponding apex, an inductance element and a resistance element in each branch connected in series, a switch for connecting the other end of one of said branches with one side 55

line, three condensers, one interposed in each side of a delta connection, three branch lines, one for each apex of the delta, one end of each branch being connected to the corresponding apex, an inductance element 60 and a resistance element in each branch connected in series, a switch for connecting the other end of one of said branches with one side of the three phase line and for connecting the other end of a second branch with a second side of said line, and for connecting the other end of a third branch with the third side of said line, means for shunting the branches of the delta simultaneously 65 while the said branches are disconnected from the line, and means for shunting each of said resistance elements while said branches are connected with said line. 70

In witness whereof I have hereunto set my hand this 7th day of May, 1924.

VICTOR E. GOODWIN.
